JERROLD C. FULLER, OF CHICAGO, ILLINOIS

CLOSURE CONSTRUCTION

Application filed January 11, 1932. Serial No. 586,033.

My invention relates to improvements in closure constructions, and it consists in the combinations, constructions, and arrangements herein described and claimed.

5 An object of my invention is to provide a self-closing spring-pressed closure construction for collapsible tubes of the type commonly used for containing semi-liquid preparations, such as, for instance, toilet creams, 10 paste, glue, and other viscous fluids.

A further object is to provide a closure construction of the type described in which a helical spring member is provided that in no way obstructs the central inner bore of 15 the neck of the tube or the tube cap.

A further object is to provide a spring-pressed closure means having a bail whereby the closure construction may be rigidly held in its closed position.

Other objects and advantages will appear in the following specification, and the novel features of the invention will be particularly pointed out in the appended claims.

My invention is illustrated in the accompanying drawing, forming part of this application, in which

Figure 1 is a fragmentary side elevational view of a collapsible tube provided with a cap member embodying the preferred form 30 of my invention,

Figure 2 is a front elevational view of the tube,

Figure 3 is a fragmentary sectional view of the tube,

Figure 4 is a fragmentary sectional view of the tube having the device of my invention secured within the neck of the tube, and

Figure 5 is an elevational view of my closure means showing the closure and the helical spring in their retracted and closed positions.

In carrying out my invention, I make use of a cap 1 which may be threadedly or otherwise connected to the neck 2 of a tube 3. The cap 1 is provided with a central bore 4 having an enlarged upper portion 5 whereby an annular shoulder 6 is provided for the purpose of supporting a helical spring 7. The inner diameter of the spring 7 may be sub-

stantially the same length as is the diameter of the lower portion of the bore 4. The helical spring may be made of any suitable spring wire. I have found it advantageous, however, to employ a spring wire having such a cross sectional area as will enable the coils of the spring to move freely in the enlarged upper portion 5 and at the same time will not unduly obstruct the passage of the cream through the central bore 4.

An annular groove 8 may be provided at the base of the upper portion 5 for the purpose of receiving a flexible split ring member 9. The lower end of the spring 7 may be soldered or otherwise secured to the split ring and the upper end of the spring may be similarly connected to a closure means 10.

The closure means 10 may, if desired, be of any size and shape adapted to close the central bore 4 at its upper end portion but it is preferably made in a somewhat dome shape, substantially as shown in the accompanying drawing.

Now referring to Figure 3, it will be noted that the upper portion of the closure means 75 10 is provided with a transverse groove 11 and that the upper portion 12 of the closure means is higher than the opposite portion 13.

This arrangement provides an abutment means whereby a bail 14 may be conveniently 80 snapped into the groove 11. The bail 14 may be pivotally connected to the cap in any suitable manner, such as, for instance, by means of a looped ring 15 which may be retained around the cap 1 by means of an external 85 annular groove 16.

Now referring to Figure 5, it will be noted that the closure means and the spring may in themselves prevent the cream or paste from flowing out of the tube when no pressure is 90 being exerted on the tube.

From the foregoing description, it is readily apparent that the collapsible tube is operatively closed except when the tube is being pressed, in which instance the flexibility of 95 the spring 7 permits the closure means 10 to move outwardly sufficiently to permit the tube contents to be ejected between the closure means 10 and the outer end of the central bore 5.

In Figure 4 I have shown a slight modification of my invention in which the closure construction is connected directly to the neck 17 of the tube 18. In this modification, the 5 split ring 9 may, if desired, be provided with an outwardly extending tubular member 19 adapted to serve as a spring guide and at the same time prevent the contents of the tube 10 from being forced between the coils of the spring which are not extended beyond the upper portion of the neck of the tube.

In this modification the helical spring 7, the closure means 10, the bail 14, and the 15 looped ring 15 may be similar in construction to those used in the preferred form of my invention. The use of the tubular member 19 is particularly advantageous when the collapsible tube or cap is provided with a very short internal bore, such as, for instance, the bore 20 of the tube 21 shown in Figure 5.

It will of course be understood that the helical spring 7 may be secured to the cap 1 and the closure member 10 in any suitable manner. If desired, the split ring 9 may be 25 omitted and the lower end of the coil may be soldered or otherwise connected directly to the inner walls of the tubular bore 4.

I claim:

1. A collapsible tube device of the character described including a tubular member forming a section of said tube, a closure member, and a helical spring member connecting the tubular member with the closure member, the tubular member being provided with a 30 central stepped bore having an outer portion and an inner portion, the outer portion of the bore being larger in diameter than the inner portion of the bore, the helical spring member being disposed within the outer portion and being adapted to hold the cover member tightly against the outer end portion of the bore.

2. A collapsible tube device of the character described including a tubular member forming a section of said tube, a closure member, and a helical spring member connecting the tubular member with the closure member, the tubular member being provided with a 45 central stepped bore having an outer portion and an inner portion, the outer portion of the bore being larger in diameter than the inner portion of the bore, the helical spring member being disposed within the outer portion and being adapted to hold the cover member tightly against the outer end portion of the bore and having an inner diameter substantially of the same length as the diameter of the inner portion of the bore of the tubular member.

3. A collapsible tube device of the character described including a tubular member forming a section of said tube, a closure member, and a helical spring member connecting the tubular member with the closure member, the tubular member being provided with 50

a central stepped bore having an outer portion and an inner portion, the outer portion of the bore being larger in diameter than the inner portion of the bore, the helical spring member being disposed within the outer portion and being adapted to hold the cover member tightly against the outer end portion of the bore and having an inner diameter substantially of the same length as the diameter of the inner portion of the bore 55 of the tubular member, the closure member being provided on its outer surface with a transverse groove, the tubular member being provided with a pivotally connected bail for engaging the transverse groove of the cover member when the cover member is in a closed position.

4. A collapsible tube device of the character described including a tubular member forming a section of said tube, a closure member, and a helical spring member connecting the tubular member with the closure member, the tubular member being provided with a central stepped bore having an outer portion and an inner portion, the outer portion of the bore being larger in diameter than the inner portion of the bore, the helical spring member being disposed within the outer portion and being adapted to hold the cover member tightly against the outer end portion of the bore and having an inner diameter substantially of the same length as the diameter of the inner portion of the bore of the tubular member, the closure member being provided on its outer surface with a transverse groove, the tubular member being provided with a pivotally connected bail for engaging the transverse groove of the cover member when the cover member is in a closed position, the closure member having an abutment means disposed on one side of said groove whereby the bail may be more readily guided into engagement with and retained in said groove.

5. A hollow cap for a collapsible tube, said cap including a tubular body member, a closure member, and a helical spring member, said helical spring member being connected at one end to said closure member, said tubular member being provided with a central stepped bore having an outer portion and an inner portion, the outer portion being larger than the inner portion of the bore, the helical spring member being disposed within said outer portion and being operatively connected at its lower end to the tubular member and being adapted to hold the cover member in a spring-pressed manner tightly against the outer end portion of said bore.

6. A hollow cap for a collapsible tube, said cap including a tubular body member, a closure member, and a helical spring member, said helical spring member being connected at one end to said closure member, said tubular member being provided with a central

stepped bore having an outer portion and an inner portion, the outer portion being larger than the inner portion of the bore, the helical spring member being disposed with-
5 in said outer portion and being operatively connected at its lower end to the tubular member and being adapted to hold the cover member in a spring-pressed manner tightly against the outer end portion of said bore,
10 said spring member having an inner diameter of substantially the same length as the diameter of the inner bore of the tubular member.
